CONTROL DEVICE

Adolf von Wangenheim, Detroit, Mich., assignor
to Detroit Lubricator Company, Detroit, Mich.,
a corporation of Michigan

Application June 20, 1936, Serial No. 86,309

17 Claims. (Cl. 200—142)

My invention relates generally to temperature responsive devices and more particularly to temperature responsive, circuit breaking devices.

One of the objects of my invention is to provide a new and improved device for preventing overheating of a heating apparatus in the event that the boiler water level decreases below a predetermined level.

Another object of my invention is to provide a device of the above mentioned character that will operate at a given time following decrease of the boiler water level to a predetermined level.

Another object of my invention is to provide a circuit breaking device operable in response to a predetermined temperature and one which will not be affected by heat generated by electric current of the circuit to be controlled.

More specifically it is an object of my invention to provide a temperature responsive, circuit breaking device in which a fusible means acts to maintain the circuit closed below a predetermined temperature, and to provide a device of this character in which the current does not flow through the fusible means so that the fusible means will not be affected by current generated heat.

Another object of my invention is to provide a device of the above mentioned character of new and improved construction to prevent conduction of heat away from the fusible means, via the metallic parts of the device.

The invention consists in the improved construction and combination of parts, to be more fully described hereinafter and the novelty of which will be particularly pointed out and distinctly claimed.

In the accompanying drawings, to be taken as a part of this specification, I have fully and clearly illustrated my invention, in which drawings—

Figure 1 is a view of my device shown in longitudinal central cross section;

Fig. 2 is a view shown in transverse cross section of my device and taken along the line 2—2 of Fig. 1;

Fig. 3 is a view partly in cross section of an end portion of my device showing the circuit controlling means in open circuit position;

Fig. 4 is a view shown in transverse cross section of my device and taken along the line 4—4 of Fig. 1;

Fig. 5 is a view shown in transverse cross section of my device and taken along the line 5—5 of Fig. 3;

Fig. 6 is a view in elevation of a heating apparatus showing one manner in which my tempera-

ture responsive, circuit breaking device may be associated in heat transfer relation with a heating apparatus, and

Fig. 7 is a view similar to Fig. 6 showing another manner in which my device may be associated in heat transfer relation with a heating apparatus.

Referring to the drawings by characters of reference and more particularly to Fig. 1, my control device includes a hollow body portion, or fitting 1 that is preferably a casting having oppositely disposed end walls 2 and 3, and a side wall preferably formed having external and oppositely disposed tubular bosses 5 and 6. The tubular bosses 5 and 6 define inlet and outlet passages 7 and 8, respectively, that open into the body 1, and these bosses may be internally threaded for connection in a fluid flow line to be hereinafter described. The end wall 2 of the body 1 is preferably formed having an extended wall portion or boss 10 of tubular form that projects into the interior of the body toward the opposite end wall 3. The tubular boss 10 defines a bore, or passage 11 that opens at one end through the outer face of the end wall 2. At its inner end the tubular projection 10 has an end wall 12 disposed adjacent the opposite end wall 3, and in the end wall 12 there is provided an opening, or aperture 13 therethrough that registers or overlies a larger opening 14 provided in the opposite end wall 3 of the body 1.

Carried by the body 1 there is a casing in the form of a tube, or sleeve member 15 that extends through the aligned openings 13 and 14 in the opposite end walls of the body and has an open end that positions within the passage 11 defined by the tubular extension 10. At its open end the tube 15 is preferably formed having an outturned annular flange 16 for seating against the inner wall surface of the end wall 12 of the tubular extension 10. The tube 15 projects externally of the body 1 and its outer end is closed. Preferably the tube 15 is formed of thin sheet metal. A gasket 17 is provided between the inner surface of the end wall 12 and the annular flange 16 of the tube 15, and this gasket is preferably formed of a material having low heat conductivity, such as rubber, to prevent conduction of heat between the tubular member and the body, for a purpose to be hereinafter described. The bore or passage 11 of the tubular extension 10 is preferably threaded to receive a tubular shaped compression member or packing nut 18 that is externally and internally threaded. The inner end of the compression member 18

preferably abuts a metallic washer 19, and between the washer and the annular flange 16 of the tubular member 15 there is provided a second gasket 20 of low heat conductivity for substantially preventing conduction of heat between the tube 15 and the body 1 via the washer 19 and compression member 18. When the compression member is tightened down, the tube 15 will be secured to the body 1 and the gaskets 17 and 20 will be compressed to seal the opening 13 in a fluid-tight manner, as well as serving to prevent the conduction of heat between the tube 15 and body 1.

The end wall 3 of the body 1 is preferably formed having an external tubular boss, or extended tubular shaped wall portion 21 that surrounds the opening 14 in the end wall 3. The inner wall surface of the tubular extension 21 is preferably spaced from the wall defining the opening 14 so as to have a portion of the outer wall surface of wall 3, around the opening 14, within the tubular boss 21 to serve as a seating surface, as at 22. Surrounding the tubular member 15 there is a second and outer tubular member, or sleeve 23 that extends longitudinally of and fits or telescopes tightly over the inner tubular member 15 in good heat transfer relation therewith. The outer tube 23, like the inner tube 15, is preferably formed of thin sheet metal. The outer tube 23 has an open end that projects into the tubular boss 21 of end wall 3 and overlies or registers with the opening 14 through wall 3. At its inner end the outer tube 23 is formed having an outturned annular flange 24 for seating 35 against the wall 22 surrounding the opening 14, the other, or outer end of the tube 23 being closed and disposed in spaced relation to the outer closed end of the inner tube 15 to provide a space 25 between the ends of the tubes. Between the annular flange 24 and the end wall 3 of the body 1 there is provided a gasket 26 which, like the previously mentioned gaskets, is of a low heat conducting material, such as rubber, to prevent conduction of heat between the outer tube 23 and the body 1. The tubular boss 21 is preferably internally threaded to receive an externally threaded compression member, or packing nut 27 of tubular form that surrounds the outer tube 23 and threads into the boss 21 for securing the outer tube 23 to the body 1 and for compressing the gasket 26 to seal the opening 14 in wall 3 in a fluid-tight manner. Preferably the inner end of the compression member 27 abuts a metallic washer 28, and between the washer and the annular flange 24 of the outer tube 23 there is provided a second gasket 29 of low heat conducting material to prevent conduction of heat between the tube 23 and the body 1 via the washer 28 and compression member 21. The outer tube 23 is formed having outwardly extending bent portions 30 providing two oppositely disposed channels that extend longitudinally and substantially coextensive of the tube 23 and cooperate with the outer surface of the inner tube 15 to provide closed passages 31. The passages 31 communicate with the interior of the body 1, and communicate with each other through the space 25 between the closed spaced ends of the tubes, providing a closed system for a cooling 70 fluid.

Disposed within and extending longitudinally of the inner metallic tube 15 there is a detachable tubular shaped member 35 formed of electric and heat insulating material, which may be 75 porcelain. The porcelain tube 35 extends through

the tubular shaped compression member 18 and preferably has an enlarged outer end portion 36 that projects externally of the body 1. Carried by and fixed to the porcelain tube 35 there is a metallic sleeve 37 that surrounds an outer end portion of the porcelain tube, the sleeve 37 having a reduced inner end portion that is externally threaded for screw threading into the tubular compression member 18 to prevent longitudinal movement of the porcelain tube. The outer end of the porcelain tube 35 is preferably closed by an end wall 38 and the inner end of the tube is preferably open and spaced from the closed end of the surrounding metal tube 15 to provide a heating chamber, or space 39 for a purpose to be hereinafter described.

Disposed within and carried by the porcelain tube 35 there is a pair of cooperable electric current conductor members, or arms 40 and 41 that extend longitudinally of the tube 35. The conductor members 40 and 41 are preferably rectangular shaped rods formed of a metal having a low resistance to flow of current, and these rods are disposed in spaced relation and extend in the same general direction, or substantially parallel to each other. The rods 40 and 41 have end portions that project externally of the porcelain tube 35 through spaced apertures in the closed end wall 38 of the tube. In the side wall of the enlarged portion 36, adjacent the end wall 38, apertures are provided for receiving screws 42 that thread into apertures in the conductor members 40 and 41 to secure the conductor members to the porcelain tube 35 and prevent longitudinal movement of the conductor members.

A sheet metal sleeve member, or cap 43 is preferably provided and fitted or telescoped over an inner end portion of the porcelain tube 35, the sleeve 43 preferably having an end wall 44 that abuts the inner end of the porcelain tube and preferably fits tightly within casing 15 in good heat conducting relation therewith. Outward longitudinal movement of the sleeve member 43, relative to the porcelain tube 35, may be prevented by providing the porcelain tube 35 with an annular groove, or slot, around its outer periphery and bending an end portion of the inner end of the sleeve inwardly to position in and engage with a side wall of the slot. Formed out of the end wall 44 of the sleeve 43 there is a tab or lug 46 that is bent so that it projects forwardly from the end wall 44 longitudinally of the sleeve, into the heating chamber 39 toward the end wall of the inner metallic tube 15. The conductor members 40 and 41 are preferably arranged in overlying relation to each other, and the lower conductor member 41 terminates within and adjacent the inner end of the porcelain tube 35. The upper conductor member 40 has an end portion 47 that projects beyond the inner end of the conductor member 41 and projects externally of the porcelain tube 35 and sleeve 43, into the heating chamber 39 through the opening resulting from the forming of the tab 46 out of the end wall 44 of the sleeve or cap 43. Carried by the conductor member 41, adjacent its inner end within the porcelain tube 35, there is an upwardly extending electric contact member 48 that is adapted to engage a similar and downwardly extending contact member 49 carried by the conductor member 40 to complete an electric circuit. When the contact members 48 and 49 are in engagement, as shown in Fig. 1, the metallic conductor member 40 is under stress acting to move 70

75

upward and away from the conductor member 41, and the lower conductor member 41 is also under stress acting to move upward or follow the upper conductor member 40. As shown in Fig. 5, the inner side walls of the porcelain tube 35 are preferably provided with oppositely disposed, longitudinally extending slots 48^a located at the bottom wall and inner end of the tube 35 to provide downwardly facing shoulders 48^b. An inner end portion of the lower conductor member 41 is enlarged and positions beneath the shoulders 48^b for engagement therewith to limit upward movement of the end of conductor member 41 and its contact member 48 carried thereby.

Secured to the inner end portion 47 of the conductor member 40 there is an extension arm 50 which may be formed out of a plate, and formed having oppositely disposed ears, or tabs 51 that may be wrapped or bent around the end portion 47 of the conductor member 40 to secure the extension arm 50 to the conductor member. Surrounding the end portion 47 of the conductor member 40, between the end portion 47 and the extension arm 50, there is provided electric and heat insulating material 52 that may be mica, or other suitable material for insulating the current conductor member 40 from its extension arm 50. The insulation 52 may be wrapped around the end portion 47 of the conductor member 40, and end portions of the insulating material may be clamped between the ends of the tabs 51, as shown in Fig. 4. The extension arm 50 projects into the heating chamber 39 toward the end wall of the inner metallic tube 15, and overlies the tab or lug 46 in close proximity thereto when the contact members 48 and 49 are in engagement with each other, as shown in Fig. 1. The conductor members or rods 40 and 41 are normally held under stress with their contact members 48 and 49 in engagement by a fuse member, designated in general by the numeral 54. The fuse member 54 preferably comprises a pair of polysided sleeve members 55 joined, or secured together by fusible material which may be solder, indicated at 56, the sleeve member slip-fitting over the extension arm 50 and the fixed arm, or lug 46. The fuse member 54 is thus positioned within the heating chamber 39 and is responsive to the temperature of the surrounding portion of the metallic tube 15. The member 43 serves as an anchor for the fuse member 54 and conducts heat from the casing 15 direct to the fuse so that the temperature of the fusible material 56 will be substantially the same as the temperature of the casing 15.

Mounted on the outer end of the porcelain tube 35 there is a conventional type of electrical fitting 58 of electric insulating material that abuts the outer end of the porcelain tube 35 and has the usual sockets 59 for receiving the externally projecting outer end portions of the conductor members 40 and 41. The electric insulating fitting 58 is preferably carried by a metallic fitting 60 that surrounds the same and has an extended sleeve portion 61, an end portion of which fits or telescopes over the enlarged end of sleeve 37 to hold the fittings thereto. The fitting 60 has a reduced and externally extending tubular portion that is preferably internally threaded to receive an externally threaded end portion of a tubular shield 61 for shielding lead wires 62 and 63 that extend therethrough and connect to the sockets 59 of the inner fitting 58. The other ends of the lead wires 62 and 63 may be connected to binding posts of a motor (not shown) for supply-

ing fuel to a heat apparatus so that when the contacts 48 and 49 are parted the motor will be deenergized and the supplying of fuel to the heating apparatus discontinued.

Referring now to Fig. 6 there is shown a heating apparatus, or furnace 65 having the usual outlet stack 66 for the passage of the products of combustion to a chimney (not shown). As one manner of installation, my device may be secured in and to the wall of the stack 66 with the metallic tubular end of the device projecting into the stack 66. The stack 66 may be provided with an aperture in its side wall to receive the tubular end of the device and the compression member 27, which also has an end portion that projects into the stack and receives a nut 67 for rigidly securing the device to the stack 66. Surrounding the compression member 27 and disposed on opposite sides of the wall of the stack 66 there are gaskets 68, Fig. 1, which are preferably formed of rubber, or formed of other suitable heat insulating material for insulating the body 1 from the stack 66. When the nut 67 is tightened, the gaskets 68 will be compressed and will seal the opening in the wall of the stack 66 in a fluid-tight manner. Secured in the upper threaded boss 5 of the body, or fitting 1, is one end of a pipe or conduit 70, the other end of which conduit is secured in and to the wall of the boiler of the furnace 65 at a point above the normal water level, indicated at 71. Secured in the lower threaded boss 6 of the body, or fitting 1 there is one end of a pipe or conduit 72, the other end of which conduit is secured in and to the wall of the boiler or furnace 65 at a point below the low water level, designated at 71^a. The upper pipe 70 is preferably connected to the boiler above the normal high water level to prevent circulation of the water by gravity through the passageways 31 which would otherwise result in heat being carried away from the metallic tubes surrounding the fuse member 54.

In Fig. 7 there is shown a manner of installing my temperature responsive device in connection with the type of furnace that has the stack leading out of the top wall thereof, and consequently above the normal or high water level. In installing my device in the above-mentioned type of furnace, the tubular end of the device containing the fusible material is preferably inserted into the furnace, or boiler, through an aperture provided in a wall 74 of the frame for the furnace clean-out door, indicated at 75. The body, or fitting 1 is connected by upper and lower pipes or conduits 76 which are secured in and to the wall of the boiler at points above and below the high and low water levels, respectively. Connecting the upper and lower conduits 76 there may be provided the usual water gauge or glass tube, as at 77.

The operation of my temperature responsive, circuit breaking device is as follows: When the level of the water in a boiler is such that water stands in the passages 31 and 25 between the inner and outer metallic tubes 15 and 23, the tubes will be prevented from reaching a temperature which would cause the fusible material to fuse. If the water in the boiler decreases to a level such that water no longer stands in the passages 31 and 25, then the temperature of the tubes 15 and 23 will increase and the fusible material 56, in the chamber 39 of the inner tube 15, will fuse at a predetermined temperature. When the fusible material 56 fuses, the inner end of the upper conductor member 40 being 75

under stress will move upwardly, and the inner end of the lower conductor member 41 also being under stress will move upwardly or follow the upper conductor member until it engages its stop 5 or shoulder 48^b. The upper conductor member 40 will continue to move upward after the lower conductor member 41 has engaged its stop 48^b and the contact members 48 and 49 will then be parted, opening circuit to the fuel supply 10 apparatus. Upward movement of the inner end of the upper conductor member 40 will be limited by engagement with the upper inner wall of the porcelain tube 35. To reset the conductors in circuit making position it is only necessary to 15 remove the porcelain tube 35, and associated parts that may be slid out of tube 15 as a unitary structure, after which the conductor members may be held with their contact members in engagement while a new fuse holding member is 20 slipped over the ends of the fixed lug 46 and the extension arm 50 of the conductor member 40. By having the lower conductor member 41 under stress such that its inner end tends to move upwardly toward the upper conductor member 25 40, it will be seen that the contacts 48 and 49 will be held in tight engagement and arcing of the contacts will be prevented.

From the foregoing description it will now be seen that I have provided a new and improved 30 temperature responsive, circuit breaking device so constructed that the temperature responsive means is not affected by current generated heat in the circuit. In regard to this point, it will be appreciated that if the current were to flow 35 through the fusible holding means of the device the current would generate heat in the fusing material, which would tend to cause the material to fuse prematurely. Furthermore, I have provided a temperature responsive, circuit breaking 40 device of such new construction as to prevent the conduction of heat away from the holding fusible material so that the fusing material will fuse within a short time period after the water leaves the passages 31 and 25. In regard to this point 45 it will be seen that if the tubes 15 and 23 were not insulated from the body 1, that heat would be conducted away from the fusing material with the result that a relatively higher temperature would have to be reached in the furnace before 50 the fusible material would fuse and break the circuit.

What I claim and desire to secure by Letters Patent of the United States is:

1. A circuit controlling device comprising a 55 pair of contact carrying members with at least one of said members being under stress acting to move away from the other of said members, contacts carried by said members and cooperable to make and break an electric circuit, a fixed arm 60 member separate from said contact members, means carried by the movable one of said contact members and overlying said fixed arm member and fusible material fusible in response to a predetermined temperature and fusing said carried means to said arm member so that said contacts are held in engagement at temperatures below said predetermined temperature.

2. A circuit controlling device comprising a 70 pair of current conducting contact carrying members with at least one of said members being under stress acting to move away from the other of said members, contacts carried by said members and cooperable to make and break an electric circuit through said members, a fixed arm 75 member separate from said contact members,

fusible material fusible in response to a predetermined temperature and holding the movable one of said contact members to said fixed arm member with said contacts in engagement at temperatures below said predetermined temperature, and means carried by said movable contact member and electrically insulating said arm member so that current flow from the movable one of said contact members will be interrupted. 5

3. A circuit controlling device comprising a 10 pair of current carrying conductor members co-operable to make and break an electric circuit, at least one of said members being under stress and acting to move relative to the other of said members to control the circuit, an extension member carried by the movable one of said members, means electrically insulating said extension member carried by the movable one of said members and separate from said conductor members and cooperable with said first-named extension member, a fusible holding means 15 removably secured to said first-named and said second-named extension members and holding said conductor members in relatively fixed relation at temperatures below a predetermined 20 temperature. 25

4. In a temperature responsive control device, a body having an inlet and an outlet for flow of fluid and having an opening in a wall thereof, a tubular member, fluid conducting means cooperable with said tubular member and in communication with said opening for the passage therethrough of fluid thereby to cool said tubular member, control means disposed within and responsive to the temperature of said tubular member, means securing said tubular member to said body, and heat insulating means between said tubular member and said body to prevent transfer of heat therebetween by conduction. 30

5. In a temperature responsive control device, 40 a hollow body portion having an inlet and an outlet for fluid and having overlying openings in oppositely disposed walls thereof, a tubular member extending through said openings, means for securing one end of said tubular member to one of said oppositely disposed walls, said tubular member extending through said hollow body and projecting externally thereof through the opening in the other of said oppositely disposed walls, heat insulating means for preventing conduction of heat between said tubular member and said body portion and also serving to seal the opening in said one wall, a second tubular member, said second-named tubular member surrounding said first-named tubular member and having an open end registering with the opening in the other of said oppositely disposed walls, said second-named tubular member cooperating with said first-named tubular member to provide a passage for fluid in communication with said hollow body, means for securing said second-named tubular member to said other wall, heat insulating means for preventing conduction of heat between said second-named tubular member and said body portion and also 55 serving to seal the opening in the other of said walls, and temperature responsive control means within said first-named tubular member and responsive to the temperature thereof. 60

6. A circuit controlling device comprising a 70 pair of stressed movable current conductor members cooperable to make and break an electric circuit, fusible means acting to hold said conductor members in closed circuit position, said conductor members having common initial move- 75

ment upon fusing of said fusible means, and means operable when said conductor members are in engaged motion to interrupt movement of one of said members so that said members will separate with a quick action.

7. A circuit controlling device comprising a pair of flexible resilient current-conducting members cooperable to make and break an electric circuit, said flexible members being under stress and each of said members acting to move in the same general direction, fusible means holding said flexible members in engagement, one of said flexible members having limited movement so that said members will be parted quickly to open the circuit after common movement in one direction upon fusing of said fusible means.

8. A circuit controlling device comprising a pair of contact carrying members, contacts carried by said members and cooperable to make and break an electric circuit, one of said members being under stress acting to move away from the other of said members to break the circuit, said other of said members being under stress acting to move in the same general direction as said one member to urge the contact carried by said other member toward the contact carried by said one member, yieldable releasable means for holding said members against relative movement, and stop means limiting movement of said other member subsequent to release of said members so that said contacts can part to open the circuit with a quick action.

9. In a temperature responsive control device, a body having an inlet and an outlet for liquid, said body also having oppositely disposed walls with one of said walls having an opening therethrough, a casing member carried by said body and projecting thereinto through the opening in said one wall, said casing member being secured at its periphery to the other of said walls, a second casing member surrounding said first-named casing member and secured at its periphery to said one wall, said casing members cooperating to provide a passage for liquid in communication with the interior of said body, and temperature responsive control means within said first-named casing member.

10. In a temperature responsive control device, a body having an inlet and an outlet for liquid, said body also having oppositely disposed walls with one of said walls having an opening therethrough, a tubular member having an open end projecting into said body through said opening, means for sealing and securing said tubular member at its open end to the other of said walls, a second tubular member fitted over said first-named tubular member in heat conducting relation thereto and closing the opening in said one wall, said second-named tubular member having an open end disposed toward said one wall, means for sealing and securing said second-named tubular member at its open end to said one wall, said tubular members cooperating to provide a passage for liquid, and temperature responsive control means within said first-named tubular member.

11. In a temperature responsive control device, a body having an inlet and an outlet for liquid, said body also having oppositely disposed walls with one of said walls having an opening therethrough, a tubular member projecting into said body through said opening and secured at one end to the other of said walls, a second tubular member fitted over said first-named tubular

member in heat conducting relation therewith, said second-named tubular member closing said opening in said one wall, means for securing said second-named tubular member at one end thereof to said one wall, said tubular members cooperating to provide a chamber for liquid, said chamber extending longitudinally of said tubular members and communicating with the interior of said body, a tubular member of electric insulating material disposed in said first-named tubular member, switch means disposed within said third-named tubular member and including a movable member projecting into said first-named tubular member, said switch means acting to open a circuit, and fusible material holding said movable member in closed circuit position at temperatures below a predetermined temperature, said fusible material being disposed in and responsive to the temperature of said first-named tubular member.

12. In a switch, a movable conductor having a contact, a contact member cooperable with said contact, said conductor being tensioned to move its contact relative to said contact member, a casing to be heated and enclosing said conductor and said contact member, a fusible element secured to said conductor, and means anchoring said element to said casing to hold said conductor under tension, said means being of heat conducting material and serving to transmit heat from said casing to said fusible element.

13. In a switch, a movable electric conductor, a contact member cooperable with said conductor to control an electric circuit, a casing to be heated and enclosing said conductor and said contact member, an anchor of heat conducting material in contact with said casing, a fusible element holding said conductor to said anchor, said conductor being held in one position relative to said contact member and movable relative thereto on fusing of said fusible element, said anchor conducting heat from said casing to said fusible element, and electric insulating material interrupting flow of current between said fusible element and said casing.

14. In a circuit controlling device, a body having an inlet and an outlet for liquid, a casing having a closed end and having a jacket for liquid, said jacket communicating with the interior of said body, a removable tubular member of electric insulating material positioned in said casing, a heat conducting tubular member carried by said first-named tubular member with its wall overlying said jacket, said second-named tubular member fitting into said casing in contact with the inner wall surface thereof, said second-named tubular member having one end spaced from the said end wall of said casing to provide a chamber, switch means in said first-named tubular member including a movable member operable to open a circuit, said movable member projecting into said chamber, said second-named tubular member having an extended portion in said chamber extending in the same general direction as said movable member, fusible material in said chamber and holding said movable member under stress to said extended portion at temperatures below a predetermined temperature, and electric insulating material interrupting flow of current between said fusible material and said casing.

15. In a temperature responsive control device, a body having an inlet and an outlet for flow of fluid and having an opening in a wall thereof, a tubular member, fluid conducting means coop-

- erable with said tubular member and in communication with said opening for the passage therethrough of fluid thereby to cool said tubular member, temperature responsive control means disposed within and having direct conduction heat exchange contact with the wall of said tubular member, means securing said tubular member to said body, and heat insulating means between said tubular member and said body to prevent transfer of heat therebetween by conduction.
16. A temperature responsive control means comprising a tubular housing member, means to cool said member, a pair of current conductor members positioned within said housing member, one of said conductor members being under stress and movable to make and break circuit with the other of said conductor members, supporting means within and in heat exchange relation with the wall of said housing member, and temperature responsive means securing the movable one of said conductor members to said sup-

porting means, said supporting means having guide means for the movable one of said conductor members.

17. A temperature responsive control means comprising a tubular housing member, means to cool said member, a tubular member of insulating material within and extending longitudinally of said housing member, a pair of current conductor members positioned within said tubular insulating member, one of said conductor members being under stress and movable to make and break circuit with the other of said conductor members, a sleeve member having an end wall and secured on said insulating member and having heat exchange relation with the wall of said housing member, and temperature responsive means securing the movable one of said conductor members to said sleeve member, said sleeve member end wall having a guide slot receiving the movable one of said conductor members.

ADOLF von WANGENHEIM.

CERTIFICATE OF CORRECTION.

Patent No. 2,172,823.

September 12, 1939.

ADOLF von WANGENHEIM.

It is hereby certified that error appears in the printed specification of the above numbered patent requiring correction as follows: Page 4, second column, line 16, claim 3, for "he" read the; lines 18 and 19, same claim, for "carried by the movable one of said mem- tension member" read from its conductor member, a fixed extension member; and that the said Letters Patent should be read with this correction therein that the same may conform to the record of the case in the Patent Office.

Signed and sealed this 10th day of October, A. D. 1939.

Henry Van Arsdale,
Acting Commissioner of Patents.

(Seal)
